UNITED STATES PATENT OFFICE.

OLIVER J. PICKARD, OF PHILADELPHIA, PENNSYLVANIA, ASSIGNOR TO JOSEPH PICKARD'S SONS CO., A PARTNERSHIP COMPOSED OF OLIVER J. PICKARD, FRED PICKARD, AND FRED A. ATKINSON, OF PHILADELPHIA, PENNSYLVANIA.

PILE WIRE.

Application filed March 9, 1925. Serial No. 14,283.

The invention relates to pile wires, and the principal object of the invention is to provide a pile wire having a cutting blade which will retain its efficiency over a longer period 5 of use than the blades of pile wires heretofore commonly used.

A more specific object of the invention is to provide a cutting blade whose effective length materially exceeds that of the blades 10 of wires as manufactured prior to my invention.

The invention further resides in certain novel details of construction as hereinafter more fully described and as illustrated in 15 the attached drawings, in which:

Figure 1 is a side view of the bladed end of a pile wire made in accordance with my invention;

Fig. 2 is a view in perspective of one end 20 of a pile wire illustrating a modification of the invention;

Fig. 3 is a view in perspective of a separately formed cutting blade adapted for use with the pile wire illustrated in Fig. 2, and

Fig. 4 is a longitudinal vertical section 25 through the assembled pile wire whose component parts are illustrated in Figs. 2 and 3.

Prior to my invention, it has been customary to provide pile wires with a cutting edge rising on an incline from the top edge 30 of the pile wire, and while the disadvantages of this form of blade have been recognized and much time and energy spent in improving it with a view to eliminating the defects, there has, so far as I am aware, been no radical departure from this general form of 35 blade.

The principal defect of this form of cutting edge resides in the fact that only a comparatively short length of the cutting edge 40 is utilized, this being at the point where the blade merges into the upper edge of the pile wire. The result has been that the blade quickly became dull and required constant 45 re-sharpening.

I have discovered that by forming the blade section so that the cutting edge extends parallel to the longitudinal axis of the wire and preferably slightly elevated 50 above the upper edge, the blade will maintain its sharpness over materially longer periods of time than heretofore, the reason for this being that with the parallel edge the

effective length is materially increased and the cutting action not concentrated at one 55 point, as with the heretofore usual form of blade.

With reference to the drawings, I have illustrated in Fig. 1 a pile wire made in accordance with my invention in which the blade portion 1 is an integral part of the wire 2. In this instance, the cutting edge extends from the point designated by the reference numeral 3 to the point designated by the reference numeral 4, the elevated inclined portion 5 of the cutting edge being provided for purposes of safety and to insure a cutting of the pile when the portion 6 of the blade which parallels the longitudinal axis of the wire 2 may have become too 70 dull to properly function. It will be understood, however, that the inclined portion 5 of the blade is not essential and may, if desired, be eliminated.

I have found that in operation when the wire 2 is withdrawn from between the piles, there is a tendency for the elevated cutting edge to draw the piles from the normal perpendicular position shown at 7 to the inclined position shown at 8, this tendency for the pile loops to be inclined also tending to draw the top of the loop down tightly upon the blade 6. The blade 6, as will be noted, is comparatively long, and by reason of its parallel arrangement, every part of it is potentially active. If, therefore, the forward edge of this blade becomes dulled in use, the other portions of the blade are still capable of cutting the pile, and the wire may be used continuously until the entire length of 90 the blade has become so dull as to be incapable of cutting the pile. In this event, where the elevated end portion 5 is provided, the latter will function to sever the piles, and this will provide an indication to the operators of the loom that the parallel edge 6 of the wire has become dulled and should be re-sharpened.

In Figs. 2 to 4, inclusive, I have illustrated another form of wire within the scope of 100 the invention. In this case, the blade 9 is formed independently of the wire 10, the latter being provided with a slot 11 adapted to receive the blade 9, as shown in Fig. 4. To secure the blade in the wire, I prefer to 105 employ solder at the shaded parts indicated

by the reference numerals 12 and 13, the application of heat for sweating this joint having no effect upon the temper of the blade. In this instance, the blade comprises 5 the extended cutting edge 6 paralleling the longitudinal axis of the pile wire and slightly elevated above the upper edge and also the elevated end portion 5 of the blade which as previously described constitutes a safety 10 element positively insuring the cutting of the pile.

I claim:

1. A pile wire comprising a cutting edge substantially parallel to the longitudinal

axis and elevated above the upper edge of 15 the pile wire.

2. A pile wire comprising a cutting edge substantially paralleling the longitudinal axis of the wire.

3. A pile wire comprising an extended 20 cutting edge substantially parallel to the longitudinal axis of the pile wire.

4. A pile wire comprising a cutting edge substantially parallel to the longitudinal axis and elevated above the top edge of the 25 pile wire and terminating at its outer end in an upwardly inclined section.

OLIVER J. PICKARD.
